US00D929683S

(12) **United States Design Patent** (10) Patent No.: **US D929,683 S**
Yu et al. (45) Date of Patent: **** Aug. 31, 2021**

(54) **DISHWASHER**

(71) Applicant: **LG ELECTRONICS INC.**, Seoul (KR)

(72) Inventors: **Seonil Yu**, Seoul (KR); **Wonjun Lee**, Seoul (KR); **Bohyun Nam**, Seoul (KR); **Kyutae Park**, Seoul (KR); **Jungkyu Son**, Seoul (KR)

(73) Assignee: **LG ELECTRONICS INC.**, Seoul (KR)

(**) Term: **15 Years**

(21) Appl. No.: **35/508,795**

(22) Filed: **Mar. 13, 2019**

(80) **Hague Agreement Data**

Int. Filing Date: **Mar. 13, 2019**

Int. Reg. No.: **DM/206378**

Int. Reg. Date: **Mar. 13, 2019**

Int. Reg. Pub. Date: **Mar. 13, 2020**

(30) **Foreign Application Priority Data**

Sep. 17, 2018 (KR) 30-2018-0043513

(51) **LOC (13) Cl.** **32-03**

(52) **U.S. Cl.**

USPC **D32/2**
